SELECTIVE CONTROL MECHANISM FOR
GOVERNOR-CONTROLLED AIRCRAFT
PROPELLERS

Howard M. McCoy, Patterson Field, Ohio

Application February 3, 1944, Serial No. 520,924

2 Claims. (Cl. 264—3)

(Granted under the act of March 3, 1883, as
amended April 30, 1928; 370, G. G. 757)

1

The invention described herein may be manufactured and used by or for the Government for governmental purposes, without the payment to me of any royalty thereon.

This invention relates to selective control mechanism for governor-controlled airplane propellers and the like, and in general aims to provide a control whereby the pilot or engineer may effect almost instantaneous changes in the propeller R. P. M. by merely pushing a button or similar switch element. Another object is to provide means which may be so adjusted that operation in resonant engine-propeller ranges is made impossible. Further objects are to provide a control mechanism which is simple, dependable, easy to adjust and maintain, and which is adapted to cooperate with known types of mechanisms for changing propeller R. P. M., without material modification of said mechanisms. It is now conventional to control the R. P. M. of a propeller by means of an engine driven governor having a coil spring and having a mechanical connection with the valve controlling the supply of hydraulic fluid to the pitch changing mechanism. (See in this connection the Martin Patent No. 2,144,429, dated January 17, 1939; MacNeil et al. Patents No. 2,218,760, dated October 22, 1940, and No. 2,299,635, dated October 20, 1942.) In one embodiment of the invention, I may add to the governor of the Martin patent a control mechanism including a source of power which makes possible as many as seven or more automatic adjustments of the propeller R. P. M. setting while the airplane is in flight by merely pushing the appropriate switch button for each desired adjustment. The invention will be readily understood by referring to the accompanying schematic drawings showing the preferred embodiment, wherein:

Figure 1 is a diagrammatic sectional elevation;

Figure 2 is a wiring diagram showing the motor control circuit of one push button switch element; and

Figure 3 is a detail in elevation showing the bank of push buttons and their legends.

Referring particularly to the drawings, 5 is an R. P. M. governor of the same type as is disclosed in Figs. 1 and 2 of said Martin patent, having flyweights 6 and a governor or speeder spring 7 whose compression is under the direct control of a slideable, but nonrotatable, abutment or piston 8 to which a valve stem 9 is fixed by means of a nut 10 and lock washer 11. The abutment or piston 8 is cup-shaped and slides in a cylindrical sleeve 12 press-fitted or otherwise secured in the governor casing 13. A cup-shaped abutment-

2

adjusting member 14, provided with external screw threads, is threaded into piston 8, which has internal screw threads, as shown. At the outer end, the abutment-adjusting member 14 is provided with a reversible worm gear 15 which meshes with a worm 16 on a shaft 17 journaled in the governor casing. Shaft 17 is an extension of a flexible shaft 18 housed in a flexible cable 19, permitting adjustment of the governor spring, 10 hence of the propeller pitch and R. P. M. of the motor, from any remote point. Valve stem 9 may operate the needle valve (not shown) which controls the flow of hydraulic fluid to the pitch-changing mechanism.

15 To provide power to drive shaft 17, thereby to vary the propeller R. P. M., I prefer to employ a reversible electric servomotor 20 with split field windings 21, and energized by a source of electricity 22 through lead 23 and conductors 58, 59 when the circuit is closed. The shaft 24 of the motor drives a pinion 25 which meshes with a gear 26 on the end of a shaft 27 which is coupled (not shown) to the end of flexible shaft 18, and is journaled in bearings provided on the arms 28, 29 of frame 30. The gear train 25, 26 is obviously illustrative of any reduction gear train, preferably of high ratio. Shaft 27 carries a reversible worm 31 which meshes with a worm gear 32 on a cam shaft 33 also journaled in frame 30, so that the 20 cam shaft is driven very slowly whenever motor 20 is energized. Secured to the cam shaft are a plurality of disk cams 34, 35, 36, 37, 38, 39 and 40, preferably arranged parallel to each other. A plurality of push buttons 41, 42, 43, 44, 45, 46 and 47 close contacts (not shown) in a switch box 48 mounted on frame 30 (or anywhere in the airplane), and a cable 49 incloses and insulates the necessary conductors which electrically connect each of the contacts in the switch box with 40 a plurality of fixed contacts 50 secured upon and insulated by the frame member 56. Switch box 48 with its various push buttons and contacts may be termed a "selector" switch since it permits the pilot to select the particular propeller adjustment which he desires for the flight conditions immediately ahead. Obviously other types of selector switches may be used. Another cable 57 incloses conductors 58, 59 connecting motor field 21 with contacts 50 and with another set of fixed 50 contacts 60, secured upon and insulated by frame member 56, which is spaced from frame member 56. There are as many contacts in each set of contacts 50, 60 as there are push buttons on the selector switch, and each pair of contacts 50, 60 55 control the motor circuit as will now be described.

Normally there is no current flowing through any of the frame-supported contacts, and the motor is normally at rest.

Let us suppose that the button 43 is depressed, as shown, to effect the proper propeller adjustment for climb or high speed. This closes the motor circuit to start the motor, which moves the piston 8 in one direction or the other and also slowly rotates the cam shaft 33 to turn cam 36. In contact with cam 36 is a cam follower 13 fixed on but insulated from a movable contact member 68, and held against the edge of the cam by compression spring 74, which is interposed between the frame and the contact member. Contact member 68 is one of a set of movable contact members (66-72 inclusive) each of which is movable between a pair of fixed contacts 50, 60 to close the circuit of motor field 21 to cause rotation of the motor in one direction or the other. Contact members 66-72 are normally in a circuit closing position against one of the fixed contacts so that depressing one of the push buttons 41 to 47 will complete the motor circuit, causing rotation of the cam shaft until the proper adjustment of piston 8 has been effected, whereupon the cam which has been active moves the corresponding contact member to neutral position, and power to the motor is immediately cut off. Each contact member 66-72 is moved by a corresponding cam of the set of cams 34-40 in the direction required by the shape of the particular cam. As will be understood from Fig. 2, the contact members may all be pivotally mounted on a rod 68a having a conductor 68b electrically connecting the switch members with the motor circuit. Each of the cams must have such a form and angular adjustment that when the corresponding push button is depressed, the motor will move piston 8 until the propeller R. P. M. is adjusted to correspond to the legend (Fig. 3) which appears on panel 81 adjacent the push button. All the other adjustments of the propeller are effected in the same way.

According to the Crane et al. Patent No. 2,311,642, dated February 23, 1943, it is old to employ a set of five or more cams mounted on a shaft rotated by a servomotor, each of said cams moving a switch member against one of two contacts to close circuits effecting rotation of the servomotor in one direction or the other, the servomotor effecting adjustment of the throttle-controlling element of the airplane engine. The amount of rotation of each cam determines the setting of the throttle. The predetermined throttle positions are selected by closing switches each associated with a cam-actuated switch member. However, the several cams must be set, during flight, by means under the control of the pilot or engineer; hence provision is made to allow slipping of each cam relative to its shaft and to lock each cam while the shaft continues its rotation, to vary the angular position of the cam to correspond exactly to the throttle position controlled thereby.

Obviously, in my arrangement of parts, the cams should be individually adjustable on the cam shaft and should be rigidly held in adjusted positions, so that the action may be very precise and certain; but as satisfactory cam adjusting and locking means are known, no disclosure is made of any particular arrangement. Furthermore, the motor circuit need not be completed through the switch members, but a control circuit of low voltage, controlled by the cam fol-

lowers, may operate the motor circuit through relays, as is well known in the art of motor control. The motor is preferably provided with a self-contained solenoid-controlled spring-loaded clutch (not shown) so that when the motor is de-energized it will be immediately declutched, whereby overrunning of the motor armature due to momentum will not affect the setting of the governor. The seven legends marked on panel 81 are obviously illustrative and may be changed to suit the different operating conditions encountered in handling different types of airplanes. While the illustrative embodiment is shown as connected with the governor of a hydraulic pitch-changing and R. P. M. regulating apparatus, the invention is readily usable with electric pitch-changing devices and may find application in various fields and industrial arts. For instance, on a multi-motored airplane or motorboat, the engineer with the aid of the described remote selective control may select a desired R. P. M. for the master synchronizer, which then governs the individual engines.

Advantages of the described control mechanism include simplification of the propeller-engine R. P. M. control for the pilot or engineer, and what is probably more important, the fact that resonant engine-propeller R. P. M. ranges, wherein prohibitive propeller blade stresses frequently occur, can be avoided. My control mechanism may be so adjusted that it is impossible for the pilot or engineer to operate in the restricted (resonant) range.

What I claim is:

1. A selective speed control mechanism for governor-controlled engine-driven aircraft propellers comprising, a propeller governor having a speed regulating means actuated by rotatable engine-driven governor weights and a speeder spring under compression, means for adjusting the compression of said speeder spring including a slidable piston-like element in abutment with said spring, means including reduction gearing for adjusting the position of said piston-like element in response to rotation of a drive shaft extending from said propeller governor to a remote control point, an electric motor, driving means connecting the remote end of said drive shaft to the shaft of said motor, a plurality of push button switches corresponding to the number of desired speed adjustments of said control mechanism, a movable contact for each of said push button switches and connected in series therewith, a pair of spaced contacts for each of the movable contacts and arranged on opposite sides of the respective movable contacts, a plurality of disk cams mounted on a common camshaft and each adapted to operate one of said movable contacts, driving means connecting said camshaft to the shaft of said motor, a plurality of energizing circuits for said motor and each including one of said push button switches, one of said movable contacts and a corresponding pair of said fixed contacts, the connections between said pairs of fixed contacts and said motor being such that closing the motor circuit through one contact of each pair causes motor rotation in one direction and closing the motor circuit through the other contact of each pair causes motor rotation in the opposite direction, and said cams being individually contoured to cause operation of said motor in such a direction and for such length of time as to produce definite and individual adjustments of the compression of said speeder

spring in response to operation of each of said push button switches.

2. A control mechanism as recited in claim 1, wherein said motor includes a split-field winding, wherein the ends of said winding connect to the opposite contacts of each of said pairs of fixed contacts, and wherein the center tap of said winding connects to the armature winding of said motor.
